UNITED STATES PATENT OFFICE.

WESLEY ROSE, OF SACRAMENTO, CALIFORNIA.

SMOKE-BONNET.

SPECIFICATION forming part of Letters Patent No. 354,937, dated December 28, 1886.

Application filed April 7, 1886. Serial No. 198,155. (No model.)

To all whom it may concern:

Be it known that I, WESLEY ROSE, a citizen of the United States, residing at Sacramento, in the county of Sacramento and State 5 of California, have invented a new and useful Improvement in Smoke-Bonnets, together with the connecting of smoke-stacks to upright boilers, of which the following is a specification.

10 My invention relates to improvements in the attaching or connecting of the smoke-stack of upright boilers in connection with the smoke-bonnet.

The objects of my improvements are to facilitate the cleaning of the flues when required and make repairs to them when needed without the trouble of removing the smoke-stack, heretofore connected with or to the smoke-bonnet. This being constructed of one 15 piece and the smoke-stack resting upon it necessitated the raising of the smoke-stack and supporting it to remove the smoke-bonnet when repairs are required at the top ends 20 of the flues, or when the flues require cleaning 25 of soot, which is quite often.

I attain my object—that of cleaning and repairing the flues of upright boilers without removing the smoke-stack—by the construction and arrangement illustrated in the accompanying drawings, in which—

Figure 1 shows an upright boiler, the smoke-bonnet removed. A section of the boiler being

cut away shows the flues and their passage through the top of the boiler where the smoke is collected by the smoke-bonnet A, Fig. 2, 35 and conducted into the smoke-stack B.

C D E, Fig. 1, are braces or rods attached to the boiler, and attached to a collar or band, F; or they may be attached to the smoke-stack B (represented by a broken section) and 40 above the collar F.

The smoke-bonnet A, Fig. 2, is constructed in sections, and is represented in sections by the letters H J. These sections have flanges, through which holes are made, by which the 45 sections are bolted or fastened together, and thus represented in the smoke-bonnet A, Fig. 2.

What I claim as my invention, and desire to secure by Letters Patent, is—

1. The rods or braces C D E, to fasten or attach smoke-stacks to upright boilers, said rods or braces attached to the top end of the boiler, the other ends of the rods attached to a collar or band, F, over which the smoke-stack slips. 55

2. A smoke-bonnet made in sections H J, in combination with a smoke-stack connected to the boiler by means of rods C D E, all for the purpose set forth, and substantially as described.

WESLEY ROSE.
